SIDE WALL CORING TOOL

Charles O. Denning and John R. Yancey, Houston, Tex., assignors to A-1 Bit & Tool Company, Inc., Houston, Tex., a corporation of Texas

Application January 24, 1948, Serial No. 4,124

6 Claims. (Cl. 255—1.4)

1

This invention relates to a core taking apparatus.

The invention disclosed herein embodies certain improvements over that type of tool disclosed in co-pending application, Serial No. 636,936, disclosing Side wall core taking apparatus, filed in the United States Patent Office December 17, 1945, by applicant, John R. Yancey et al.

An object of the invention is to provide apparatus whereby cores, or samples, may be cut from the side wall of a bore hole and withdrawn to the ground surface for inspection and which apparatus may be readily jarred loose in case it should become stuck in the bore in lowering or removing the tool.

It is another object of the invention to provide a tool of the character described wherein provision is made for the necessary circulation of drilling fluid through the core barrel while the core is being cut from the side wall and which, when the core barrel has reached the limit of its downward movement, will also allow circulation of said fluid around the barrel as well as through it.

A further object of the invention is to provide in a side wall core drill a tubular driving assembly with a whipstock having a swivelling connection therewith, a core drill mounted in the assembly and having a driving connection therewith with a fluid passageway through the drill and a seal in the driving assembly through which the drill slides with fluid release ports in the drill whereby the hydraulic pressure required to feed the drill into the formation will be released when the core is secured.

It is a still further object of the invention to provide in a rotary type side wall core drill for use in bore holes, a tubular driving assembly and a whipstock having a swivelling connection therewith with a core drill mounted axially in the assembly and having a driving connection therewith with a restricted fluid passageway through the drill whereby the drill may be fed out into the sidewall of the bore by hydraulic pressure with auxiliary ports in the drill and means to open said ports to remove the flow restriction.

The invention embodies a novel type of whip stock for deflecting the core barrel and which is also adapted to engage with the core barrel to withdraw the core barrel from the well should it become detached from the apparatus during the core taking operation.

In this type of tool, the core taking apparatus, including the whip stock, or deflector, is assem-

2

bled with the drill stem with the whip stock suspended from the stem and the core barrel driven by the stem but wherein the coring tool is independently insertable into and withdrawable from the stem while the stem remains in the well bore.

Other objects and advantages will be apparent from the following specification which is illustrated by the accompanying drawings, wherein:

Figures 1, 2 and 3 are upper, intermediate and lower sections of the apparatus shown in section.

Figure 4 is a cross-sectional view taken on the line 4—4 of Figure 1.

Figure 5 is a cross-sectional view taken on the line 5—5 of Figure 2.

Figure 6 is a cross-sectional view taken on the line 6—6 of Figure 2.

Figure 7 is an elevational view of the tool, and

Figure 8 is a cross-sectional view taken on the line 8—8 of Figure 3.

Referring now more particularly to the drawings, the numeral 1 designates a tubular drill stem which extends to the ground surface. The lower end of the drill stem is formed with a special tubular driving section 2 which is connected to the drill stem by the coupling 3. The section 2 has a plurality of inside longitudinal ribs 4 extending from the upper end to the lower end thereof and spaced apart.

Connected to the lower end of the driving section 2 there is an inwardly thickened reducing nipple 5 and connected to the lower end of the nipple 5 there is a coupling 6 which contains an annular packing ring 7 which is clamped between the lower end of the nipple 5 and an internal annular shoulder 8 within the coupling 6. Therefore when the coupling 6 is screwed onto the nipple 5 the seal ring 7 will be placed under the required compression. The passage-way through the above described assembly of the nipple 5 and coupling 6 is of substantially the same inside diameter throughout.

The whip stock or deflector is designated generally by the numeral 9. It has a swivelling connection with the drill stem. This connection is formed between the tubular nipple 10, whose upper end is connected to the coupling 6, and the tubular housing 11, whose lower end is connected to the whip stock 9.

The lower end of the nipple 10 extends into the housing 11 and within said housing is enlarged forming the external annular, upwardly facing shoulder 12 which supports an anti-friction bearing assembly 13 which is retained in place by the gland 14. This gland is screwed into the upper end of the housing 11.

Countersunk into said gland and surrounding the nipple 10 there is a seal ring 15 and beneath said seal ring there are the roller bearings 16 mounted in the gland around the nipple 10.

The lower end of the nipple 10 is supported on the anti-friction bearing assembly 17 which, in turn, is supported on an inside annular shoulder 18 formed by the inwardly thickened lower end of the housing 11.

Between the lower end of the nipple 10 and said housing 11 there are the radial roller bearings 19 which are countersunk into the said nipple and countersunk into the inwardly thickened lower end of the housing 11 there are the annular seal rings 20.

Screwed into the lower end of the nipple 10 there is a tubular hood 21 having an annular inside seat 22 and said hood is provided with fluid passageways 23 around said seat and passing downwardly therethrough and providing for the free flow of fluid. The seal rings 20 form fluid tight seals around the lower end of the hood 21.

An efficient swivel connection is thus formed between the drill stem and the whip stock whereby the latter is supported in the well by the former.

The whip stock as a whole is shown in detail in Figures 2 and 3 and is substantially similar to that type of whip stock shown in the pending application above referred to. It comprises a tubular shell 24 whose lower end is downwardly tapered and above said taper is provided with a longitudinal side slot 25 which extends to its lower end; the upper end of the shell 24 is connected to the housing 11.

Secured on the outside of the shell opposite said slot there is a longitudinal rib 26 and on opposite sides of the slot there are the longitudinal ribs as 27 which are secured to the outer side of the shell. These ribs 26 and 27 engage the formation of the well bore to hold the whip stock centered in the bore hole.

Within the shell 24 there is a guide which is rectangular in cross section. This guide is fitted downwardly within the shell and is composed of side plates 28, 28 whose margins are beveled to fit within the shell, and the cross plates 29, 29. The plates 28 and 29 are secured together preferably by welding. This guide is preferably flared downwardly as indicated in Figures 2 and 3. The plates 28 carry a transverse stop 30 which rests on a corresponding transverse stop 31 to support the guide in the shell; said stop 31 being carried by the shell.

Within the guide, and arranged at the lower end thereof, is a deflector plate 32. This plate is arranged opposite the slot 25 and declines forwardly. It is supported by the transverse upper and lower pins 33, 34 which extend transversely through the deflector plate and whose ends are anchored to the respective side plates 28.

The lower pin 34 is shearable for a purpose to be hereinafter stated.

The upper face of this plate, at its lower end, is provided with an insert of hard wear-resisting material 35 as shown in Figure 3. At the upper end of the deflector plate 32 the guide plate 29 is inwardly thickened and is of a general triangular shape in vertical cross-section and whose upper face is approximately flush with the upper face of the deflector plate 32 thus forming a guide 36.

Anchored to the front plate 29 of the guide, above the slot 25, there is a flexible guide 37

whose lower end is free and is outwardly turned. The slot 25 extends on down and partly across the lower end of the shell 24, for a purpose which will be hereinafter explained, and the lower end of said slot beneath the lower end of the deflector plate 32 is closed by a thin metallic skirt 38, as shown in Figure 3, to prevent the entrance of foreign matter into the whip stock shell beneath said deflector plate assembly.

10 The core taker proper will now be described in detail:

Generally speaking, it comprises a bore barrel 39 and a sectional driving stem consisting of the upper tubular section 40 and the lower tubular section 41. These sections are connected by a universal coupling designated generally by the numeral 42 and the core barrel is connected to the lower end of the section 41 by a similar universal coupling 43. Only one intermediate section of the driving stem is illustrated, although it is apparent that this number may be varied if found practical. The upper section of the driving stem is formed of the upper and lower tubes 44, 45. These tubes are connected by an inside coupling 46 which is formed with an external annular stop 47 of a diameter to land on and be supported by the seat 22 as shown in Figure 2.

30 Screwed onto the upper end of the tube 44 there is a head 48 which has a longitudinal, radially extended, lug 49 adapted to work between the inside ribs 4 of the driving section 2.

The upper end of the head 48 carries a knob 50 provided to be engaged by a grapping tool 35 which may be lowered through the drill stem by means of a wire line.

40 Located within the tube 45 there is a tubular screen 51 whose upper end is closed. This screen is of smaller diameter than the tube 45 and is perforated throughout its length. Secured to the lower end of this screen 51 there is a tubular valve 52 which fits closely within said tube 45 and is provided with external annular seal rings 53 and 54 which are spaced apart and which 45 form seals with said tube 45. This valve is pinned in place by means of a frangible cross pin 55 and the tube 45 has a plurality of outlet openings 56 which the valve 52 normally closes.

50 The screen 51 is provided for the primary purpose of screening out any solid material from the fluid flowing downwardly through the driving stem of the core taker.

55 The universal couplings connecting the sections of the driving stem and connecting the driving stem to the core barrel are similar, as hereinabove indicated. Similar flexible tubes as 57 extend axially through these couplings and the ends of these flexible tubes are anchored in place to the corresponding driving stem sections in any 60 preferred manner as is fully disclosed in the co-pending application above referred to.

The upper end of the core barrel 39 is screwed onto a coupling 58 and screwed onto the lower end of the barrel there is a core-forming tool or 65 drill 59 having the conventional central core-receiving opening through which the core enters the sample container in the barrel 39.

70 Mounted on the tubular driving assembly there is a tubular body 60 which is pinned in its upper position to the coupling 6 by means of a frangible pin 61. The coupling 6 is provided with the external vertical keyways 62 which extend from the lower end of said coupling to near the upper end thereof where they terminate in the shoulders 63, 63 and anchored to the body 60 are the

inwardly extended keys 64 whose inner ends project into said keyways to prevent the body 60 from turning relative to the tubular driving assembly, but which permit a limited longitudinal movement of said body when the pin 61 is sheared. When the body 60 is pinned in place its upper end is spaced the required distance above the upper end of the tubular nipple 10 as more clearly indicated in Figure 7.

The lower end of the tubular body 60 forms an anvil and it is also provided with the clutch teeth 65.

The upper end of the gland 14 forms an impact hammer and is also provided with the clutch teeth 66.

In operation the operating string 1, with the whip stock apparatus suspended therefrom, may be lowered to the desired location in the well so as to locate the whip stock at the point where a sample is to be taken. The sample taker may then be dropped through the string; or it may be lowered through the string by a wire line releasably connected to the knob 50. The lower end of the core barrel will land on, and be deflected by, the deflector plate 32 of the whip stock 25 as indicated in Figure 3. The flexible guide 31 will operate to guide the core barrel and hold it in the proper angular relation.

When lowered to the position to begin taking a core the operating string may be rotated and the whip stock will be held against rotation by the engagement of the core cutter head 59 with the formation while the core taker will be rotated by the engagement of the driving section 2 with the lug 49 of the head 48.

Fluid pressure may be applied by a pump at the ground surface, through the operating string and against the head 48, thus gradually forcing the core taker downwardly as it is rotated and a bore will be formed by the cutter head 59 in the side wall of the well bore and a core, or sample, will be taken and forced into the core-receiving chamber of the core barrel 39.

While the coring operation is being carried on, fluid will enter through a side opening 67 in the head 48 and will pass on down through the driving stem 44, 45 and through the screen 51 and on down around the sample in the core barrel to the cutter head 59 to lubricate and cool said cutter head 59 and carry away the cuttings; however, it will be noted from an inspection of Figure 1 that the upper tube 44 of the driving stem is provided with radial openings 68 which, upon beginning of coring operations, are above the seal ring 7 but they will eventually pass through said seal ring and beneath it upon completion of the core and thereupon a portion of the drilling fluid will pass out through the openings 68 and around the driving stem and on down through the fluid passageways 23 and around the core former. The coupling 6, opposite the openings 68 may be lined with a sleeve, or liner, 6a of wear resisting material.

When the core barrel has reached the limit of its downward movement the annular stop 47 will land on the seat 22 to stop the further downward movement of the core taking apparatus. Attention is called to the fact that while taking the core the deflector is suspended from the operating string and is held at substantially the same level during the coring operation and, therefore, means for anchoring the deflector to the walls of the bore hole are not necessary and are dispensed with. During the coring operation the string 1 is rotated to rotate the coring ap-

paratus but is not moved downwardly in the bore hole.

In carrying on coring operations the core barrel 39 may become detached from the apparatus and for that reason the upper end of said barrel is enlarged forming an external annular shoulder 69 and the lower end of the slot 25 is narrowed and the lower end of the barrel is of a diameter to fit snugly through the narrowed end of the side slot 25 so that should the barrel become detached it will not be lost in the well but upon upward movement of the whip stock the pin 34 will be sheared and the deflector 32 will swing on the pin 33 to vertical position and the thin skirt 38 will be displaced and the lower end of the shell 24 on opposite sides of the slot 25 will engage the shoulder 69 and the core barrel 39 will be withdrawn as the apparatus is removed from the well bore.

During coring operations strong gas pressure is sometimes encountered which, if uncontrolled, may cause a blowout.

In case such pressure is encountered the pump at the ground surface, which forces the drilling fluid down through the drill stem, may be speeded up thus increasing the pressure against the upper end of the screen 51 sufficient to shear the pin 55 and said screen will be moved downwardly carrying the valve 52 beneath the openings 56 and this will allow the flow of additional drilling fluid down through the drill stem and on down through the whip stock so as to build up pressure in the well sufficient to overcome said gas pressure.

In lowering the drill stem and whip stock into the well, or in withdrawing the same from the well, the apparatus may become stuck in the well bore. If the body 60 becomes stuck the drill stem 1 may be pulled upwardly thus causing the pin 61 to shear and causing the hammer to strike the anvil thus, possibly, jarring said body loose. By lowering the drill stem and suddenly moving it upwardly these strokes may be repeated until the body is released.

It may happen that the whip stock 9 may become stuck in the bore and in such event the drill stem may be lowered, shearing the pin 64, and carrying the teeth 65 into mesh with the teeth 66 and thereupon by turning the drill stem back and forth the whip stock may be correspondingly turned back and forth until it has been released and may be withdrawn; or the whip stock may be jarred downwardly by alternately taking a tension on, and releasing, the drill stem so as to cause the anvil to successively strike the hammer.

In the manner above indicated the whip stock may often be released and removed from the well bore in case it should become stuck.

The drawings and description disclose what is now considered to be the preferred form of the invention. This disclosure, however, is by way of illustration only, while the broad principle of the invention will be defined by the appended claims.

What we claim is:

1. A core taking device for wells comprising; a whip stock including a shell having a side opening and a deflector in the shell; an operating string having a rotatable connection with the whip stock; a core taker including a barrel and a driving stem adapted to be lowered through the operating string into co-acting relation with the deflector to deflect the barrel through the opening, said driving stem having an inlet opening

in communication with said operating string and a side outlet opening; a tubular valve in the stem; frangible means normally holding said valve in position to close said side outlet opening; a tubular screen connected to the valve and extending up into the driving stem; a driving connection between the string and stem whereby the stem and barrel may be rotated.

2. Sample taking apparatus for wells comprising, a deflector, a tubular operating string having a rotatable connection with the deflector and having an inside annular stop, a sample taker including a barrel and driving stem adapted to be lowered through the string into co-operating relation with the deflector to deflect the barrel, said sample taker having a channel for fluid therethrough and also having an external stop arranged to land on said internal stop to arrest the downward movement of the sample taker, said driving stem having an inlet in communication with said operating string and a side outlet opening, packing means between said driving stem and said operating string adapted to close said outlet opening when said stops are out of contact and to open said outlet opening to permit the passage of fluid downwardly through said string about said stem when said stops are in contact.

3. A core taking apparatus comprising, a whip stock; an operating string of pipe to the lower end of which the whip stock has a swivelling connection; a core taker including a driving stem formed of sections flexibly connected together and a core barrel flexibly connected to the stem to be moved laterally, by the whip stock into the side wall of a well bore upon downward movement of the core taker; said driving stem having an inlet port in communication with said operating string and a side outlet port; a sleeve valve in the stem; frangible means connecting said valve to said stem in position to close said side port; a screening element on the valve formed with an area against which the pressure fluid flowing through the stem may act to shear said connecting means to allow a downward movement of the valve to open said side port and means for rotating the core taker from the string.

4. In a rotary type side wall core drill for use in bore holes, a tubular driving stem, a whipstock, a swivelling connection between said stem and said whipstock, a core drill mounted axially in said stem, and a driving connection between said stem and said drill, a restricted fluid passage-

way through said drill whereby said drill may be fed out into said side wall by hydraulic pressure, auxiliary ports in said drill, and means to open said ports to remove the flow restriction.

5. Sample taking apparatus for wells comprising, a deflector, a tubular operating string, a rotatable connection between said deflector and said string, an inside stop in said string, a sample taker including a barrel and driving stem adapted to be lowered through the string into co-operating relation with the deflector to deflect the barrel, a driving connection between said sample taker and said string, said sample taker having a restricted channel for fluid therethrough and also having an external stop arranged to land on said internal stop to arrest downward movement of the sample taker and co-operating means between the string and stem to remove said restriction when the core taker lands in said arrested position.

6. In a side wall core drill for use in bore holes, an operating string of pipe, a tubular driving stem connected to said string and slidably disposed axially in said string to form therewith an annular passage about said stem, a whipstock, a swivelling connection between said string and said whipstock, a core drill flexibly connected to said stem to be moved laterally by the whipstock into the side wall of a well bore upon downward movement of said stem, said stem having an inlet in communication with said string and an outlet communicating with said passage, and sealing means in said passage effective in one position of said stem to close said outlet and in another position of said stem to open said outlet.
